(57) **CLAIM**

The ornamental design for a power bank, as shown and described.

DESCRIPTION

1. Power bank
2. Power bank
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Perspective
- 2.1 : Perspective
- 2.2 : Perspective
- 2.3 : Front
- 2.4 : Back
- 2.5 : Left
- 2.6 : Right
- 2.7 : Top
- 2.8 : Bottom
- 2.9 : Perspective

(Continued)

Fig. 1.1 is a perspective view of a first embodiment of a power bank showing my new design; fig. 1.2 is another perspective view thereof; fig. 1.3 is a front view thereof; fig. 1.4 is a rear view thereof; fig. 1.5 is a left side view thereof; fig. 1.6 is a right side view thereof; fig. 1.7 is a top view thereof; fig. 1.8 is a bottom view thereof; fig. 1.9 is a perspective view showing a use state of fig. 1.1; the broken lines are included to show features that form no part of the claimed designs.

1 Claim, 18 Drawing Sheets
